UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

BOILER.

Original application filed April 15, 1919, Serial No. 290,180. Divided and this application filed November 18, 1920. Serial No. 424,856.

In the drawings, Fig. 1 is a vertical transverse section through a boiler showing one embodiment of my invention and Fig. 2 is a side view of the economizer with parts removed.

Like reference characters indicate like parts throughout the drawings.

My present application is a division of my application Serial No. 290,180, which 10 was filed in the Patent Office on or about April 15, 1919.

Referring to the drawing, the numeral 1 designates an upper bank of horizontally inclined water tubes, and 2 a corresponding lower bank shown as comprising three rows. The combustion chamber 3' below the lower bank of tubes extends substantially the entire length of the tubes, the boiler being fired at both front and rear by underfeed 15 stoker mechanisms 3 of well known construction. The lower ends of the tubes of alternate vertical rows of the upper bank are connected to downtake headers 4 and 5, and the upper ends of said tubes are connected to uptake headers 6 and 7, while the lower ends of the tubes of alternate vertical rows of the lower bank are connected to header sections 8 and 9, and the upper ends of said tubes are connected with 20 drop-leg extensions 6' and 7' of the uptake headers 6 and 7. The headers 4 and 5 are connected to the header sections 8 and 9, respectively, by relatively long nipples 10 and 11, and the upper ends of the headers 25 4 and 5 are connected to a transverse steam and water drum 12 by nipples 13 and 14. Said drum is also connected to the uptake headers 6 and 7 by two rows of horizontal tubes 15. A baffle 16 extends over the upper 30 row of tubes 2 from the header sections 8 and 9 for a portion of their length, and a transverse baffle 17 divides the upper bank of tubes into two passes, so that the gases will flow over the banks of tubes in the 35 general direction indicated by the arrows to the outlet connection 18, the latter delivering the gases to an uptake flue in which is located an economizer comprising a series of horizontal boxes 19 connected 40 by tubes 20, the tubes in adjacent rows preferably being staggered with respect to each other for their entire length as illustrated. This economizer may constitute the high pressure stage of an economizer sys-

tem, the low pressure stage of which is not shown. The tubes and boxes of the economizer are preferably of wrought iron or wrought steel to withstand the high boiler pressure to which they are subjected. As shown, it is divided into three sections, 45 water entering the uppermost section through the pipe 21 and leaving said section through the pipe 22, by which the water is delivered to the middle section and leaves the latter through the pipe 23, which delivers it to the lowermost section, from which the water flows through a pipe 24 to the steam and water drum 12, the flow of water through the pipe 24 being controlled 50 by a feed valve 24' for regulating the supply of water to the boiler.

By arranging the economizer in the way described, the advantages of the counter-flow principle are secured as the uppermost of the three sections which come in contact with the coolest gases will contain the coolest water, the middle section which comes in contact with the gases of an intermediate temperature somewhat hotter water, and the third and lowermost section, which comes in contact with the hottest gases will contain the hottest water. Each section is fed at the lower part and the heated water passes away from the upper part. This results in the water flowing upwardly throughout each section, which gives a more even distribution between the different tubes than should the water be fed downwardly through the sections. Again, by feeding the water upwardly throughout 65 each section in the way described, the water flowing through each tube flows in a slightly upward direction and tends to more thoroughly sweep out any air or contained gases from the tubes than would be the case 70 should there be a downward flow.

By causing the water to flow in an upward direction in the economizer, the water is better distributed through the various tubes than would be the case if it flowed downwardly. Furthermore, as will be apparent from Fig. 2, each pass of the water across the flue is confined to a single row of horizontally extending tubes, and the velocity of the water is high as compared with what it would be if it were permitted to flow through two or more rows in making 80 a single pass across the flue. The high ve-

lacity of the water through the tubes itself assists in causing an even distribution of the water across the tubes of a row and further assists in sweeping out any air or contained gases that might tend to cling to the walls of the tubes which result is further facilitated by inclining the tubes upward slightly in the direction of the flow. The arrangement, therefore, has the advantages resulting from a rapid flow of the water through the tubes while maintaining an even temperature of the water from side to side in each horizontal row of tubes.

By making the internal cross sectional area of the connections leading downward from one section to another less than the combined internal cross sectional area of the plurality of tubes connecting the boxes and through which the water flows upwardly in parallel, as shown, the velocity of the water flowing downwardly through the connections is higher than that in the economizer tubes and is sufficiently high to carry along any gas or vapor from the top of each section to the bottom of the next section below.

A primary superheater 25 is preferably located in the triangular space above the upper bank of tubes, and a secondary superheater 26 is located in the secondary combustion chamber between the two banks of tubes, the steam from the drum 12 being delivered through the pipe 27 to the superheater 25 and from the latter through a pipe 28 to the upper box of the superheater 26. The superheated steam is delivered to the main through a connection from the lower box 26' of the superheater 26. A second superheater 29 is also located in the secondary combustion chamber between the two banks of tubes, to the upper cross-box of which steam is delivered from one of the stages of a steam turbine, and the steam so re-superheated, returned through a connection from the cross-box 29' to a lower pressure section of the turbine. All of these superheaters comprise cross-boxes connected by U-tubes and all are arranged with their upper legs substantially horizontal so that they can be flooded and drained. Also, the loops for the superheaters 26 and 29 should be so proportioned that they can be introduced by passing them between the nipples 10 and 11.

What I claim and desire to secure by Letters Patent of the United States is:—

1. In combination, a flue having a vertical portion through which the heating gases from the boiler pass upwardly, an econo-

mizer having a plurality of sections located in said flue, each section comprising a plurality of rows of substantially horizontal tubes spaced uniformly from side to side of the flue through which the water and any contained gases flow back and forth, first flowing in parallel through the lowermost row of tubes of each section and then back and forth in parallel through successive rows until it is discharged from the uppermost row of tubes of each section, and connections for causing the entire amount of feed water to flow first through the uppermost section and successively through the other sections and into the boiler.

2. In combination, a flue having a vertical portion through which the heating gases from the boiler pass upwardly, an economizer having a plurality of sections located in said flue, each section comprising a plurality of rows of substantially horizontal tubes spaced uniformly from side to side of the flue through which the water and any contained gases flow back and forth, first flowing in parallel through the lowermost row of tubes of each section and then back and forth in parallel through successive rows until it is discharged from the uppermost row of tubes of each section, and connections shielded from the heating gases for causing the entire amount of feed water to flow first through the uppermost section and successively through the other sections and into the boiler, the internal cross sectional area of the connections between sections being less than the sum of the internal cross sectional areas of the tubes in a single horizontal row.

3. In combination, a flue having a vertical portion through which the heating gases from the boiler pass upwardly, an economizer having a plurality of sections located in said flue, each section comprising a plurality of rows of substantially horizontal tubes spaced uniformly from side to side of the flue through which the water and any contained gases flow back and forth, first flowing in parallel through the lowermost row of tubes of each section and then back and forth in parallel through successive rows until it is discharged from the uppermost row of tubes of each section, and connections shielded from the heating gases for causing the entire amount of feed water to flow first through the uppermost section and successively through the other sections and into the boiler.

DAVID S. JACOBUS.
